SKI BINDING

Guido Reuge, Ste.-Croix, Switzerland

Application February 27, 1948, Serial No. 11,620
In Switzerland March 24, 1942Section 1, Public Law 690, August 8, 1946
Patent expires March 24, 1962

7 Claims. (Cl. 280—11.35)

1

The present invention relates to ski bindings comprising a heel pull member which has its front portion in places permanently connected to the ski and which includes side parts extending along the ski and at least one yoke or bridge connecting the side parts of the heel pull member across the top face of the ski, means being provided to co-operate with the heel pull member at places behind the places of permanent connections of the heel pull member with the ski for preventing deflection of the heel pull member in front of said co-operating places and for causing a diagonal tension to be operative upon the heel of the boot fastened in the binding, said means being operable by a manipulating device located outside the area of the boot.

According to the invention the yoke connecting the side parts of the heel pull member is formed in such manner and positioned on the heel pull member in such position that the yoke provides a surface contacting with the standing area of the sole of the boot fastened in the binding and is adapted to be engaged on the ski by means of the manipulating device, when the yoke is being depressed on the ski, without the necessity of opening the binding, thus providing a temporary rearward connection of the heel pull member with the ski.

It is an object of the invention to provide a ski binding including means to allow the change from normal or horizontal tension upon the heel of the boot fastened therein to diagonal tension and vice versa by means of a single manipulating device located outside the area of the boot, which device is preferably secured on the top face of the ski in front of the toe guide cheeks and which is operable without it being necessary to open the binding. The manipulating device may be provided with means which render it possible to switch the device, for instance by the point of a ski pole, so that the user need not bow down. Further means may be provided to firmly apply the yoke against the standing area of the boot sole and, in addition, to increase the effect of the diagonal tension in certain instances.

Other features and advantages of the invention will more fully appear during the course of the following specification, wherein several embodiments of the invention will be explained.

In the drawings:

Fig. 1 is a top plan view of one embodiment of this invention.

Figs. 2 and 3 show another embodiment in side view and top view, respectively.

Fig. 4 is a side view of another embodiment equipped with another manipulating device.

2

Referring to the reference characters in the drawings, in all the illustrated embodiments of the ski binding numeral 1 represents a portion of a ski which carries toe guide cheeks 2 and a heel pull member constituted by one or two cables 3 extending on either side along the ski and a heel screw spring 4 connecting the rear ends of cables 3. In some embodiments, a tightener 5 for closing and opening the binding is provided between spring 4 and one of the rear ends of cables 3. The heel pull member is permanently connected to the ski 1 or, in some instances, to the toe guide cheeks 2, at the places 6, behind which the heel pull member is normally adapted to be swivelled up and down.

The embodiment shown in Fig. 1 comprises a heel pull member having its front part formed by a flexible lamina 26. The front end of lamina 26 provides two hinges 62 with the toe guide cheeks 2 and the rear end forms a yoke 27 to which on either side of ski 1 are secured cables 3 which constitute together with a heel spring 4 and a tightener 5 the rear part of the heel pull member. This lamina 26 can roll together with the boot sole on the top face of ski 1 and can be locked down to the ski by means of a pair of switching latches 28 which are adapted to engage the rear end or yoke 27 of lamina 26. A front lever 29 having a somewhat cranked shaft 30, as shown in Fig. 1, which is connected via a push rod 31 with swinging latches 28 serves to operate the latter. When lamina 26 together with yoke 27 are depressed on ski 1 and lever 29 is turned forward, latches 28 will lock lamina 26, thus enabling the heel pull member to exert a diagonal tension upon the heel of the boot, without it being necessary to open the binding beforehand. In order to secure lever 29 against unintentional actuations the moving parts of the locking device may be assembled, for instance, so as to provide sufficient friction.

The embodiment shown in Figs. 2 and 3 includes a yoke 38 integral with the rear end of a flexible lamina 48 which is hinged to a manipulating lever 49 mounted in front of the toe guide cheeks 2 and which forms the front part of the heel pull member, whereby two tongues 50 in the range of cheeks 2 overlap the lateral border of lamina 48 to form the permanent attaching places wherein lamina 48 is slidably attached to ski 1. Cables 3 together with heel spring 4 and tightener 5 are secured to yoke 38 to constitute the rear portion of the heel pull member. When tightener 5 is closed, lamina 48 will be withdrawn so far that stops 51 provided thereon will be applied against tongues 50, whereby lever 49 takes

the position shown in dotted lines. Besides, yoke 38 is provided with eyes 39 as in the preceding example, which may engage in hooks 40 screwed to ski 1, when yoke 38 is depressed on the ski by boot sole 10 and simultaneously lever 49 will be rocked into the position shown in full lines, under elongation of heel spring 4. Thus heel 10a is placed under diagonal tension. Lamina 11 may extend further backward, for instance below heel 10a.

Fig. 4 shows a modification of the manipulating device which comprises a tightening lever 56 having an axle 57 provided to be turnably seated in either of two pairs of bearings 59 and 60 of a support 58 which is U-shaped in cross section and is mounted on ski 1 in front of cheeks 2. Cables 3 of the heel pull member are connected with tightening lever 56. The bearings 59 and 60 in each side wall of support 58 communicate with each other through a guide slit 61 having the shape of an upwardly bent knee. A lever 62 engages with its one arm the axle 57 of lever 56 from below, whereby when the other arm of lever 62 is depressed, axle 57 will be lifted off bearings 59 along slit 61 up to the knee thereof and by the action of heel spring 4 it will be pulled from there along the remaining part of slit 61 into bearings 60. When tighter 56 is depressed with its axle 57 in the front bearings 59, a diagonal tension upon heel 10a will be obtained by the engagement of yoke 38 in the hooks 40. When tighter 56 is depressed with its axle 57 in the rear bearings 60, the binding is closed under normal tension in the heel pull member and, when tighter 56 is swivelled up, the binding is open.

In Fig. 4 the compression spring 53 may be omitted and the desired change of length in the heel pull member can be performed exclusively by the elasticity of heel spring 4.

It is obvious that still further changes and modifications may be made in the details of construction and design of the above described embodiments of this invention without departing from the spirit thereof, such changes and modifications being restricted only by the scope of the following claims.

What I claim is:

1. A ski binding comprising toe guide cheeks for the boot, a heel pull member which has its front portion in places permanently connected to the ski and which includes side parts extending along the ski and at least one yoke or bridge connecting said side parts across the top face of the ski, said yoke being adapted to be applied against the standing area of the sole of the boot fastened in the binding, latch-like means positioned upon the ski adjacent to the position whereat said yoke encounters said ski for engaging said yoke at places behind said places of permanent connection of said heel pull member with the ski to prevent deflection of said member between said permanent connections and said yoke inclusive, and a manipulating device located outside the area of said boot for effecting and releasing the engagement between said engaging means and said yoke, when the latter is being depressed by said boot on the ski, without the necessity of opening the binding.

2. A ski binding as claimed in claim 1, wherein the means for engaging the yoke are constituted by swinging latches which are operatively connected with the manipulating device and which are adapted in locking position to arrest said yoke depressed on the ski.

3. A ski binding comprising toe guide cheeks for the boot which are affixed on the ski, a heel pull member having its front portion in places permanently connected to the ski and including side parts which extend along the ski, a yoke secured to said side parts to connect them across the top face of the ski and providing a surface to contact with the standing area of the sole of the boot fastened in the binding, a spring element forming a portion of said heel pull member behind said yoke, latch-like means affixed to the ski adjacent to the position whereat said yoke encounters said ski for engaging said yoke at places behind said places of permanent connection of said heel pull member with the ski to prevent deflection of said member between said permanent connections and said yoke inclusive, and a manipulating device located outside the area of said boot for effecting and releasing the engagement between said engaging means and said yoke, when the latter is being depressed by said boot on the ski, without the necessity of opening the binding, said heel pull member being connected to said manipulating device to be submitted to elastic length variations in longitudinal direction of the ski by said manipulating device.

4. A ski binding as claimed in claim 3, wherein the heel pull member has its portion extending from its permanent connections to the yoke formed by a flexible lamina which is endwise reciprocable on the top face of the ski and operatively connected with the manipulating device.

5. A ski binding comprising toe guide cheeks for the boot which are affixed on the ski, a heel pull member having its front portion in places permanently connected to the ski and including side parts which extend on either side along the ski, a yoke secured to said side parts to connect them across the top face of the ski and providing a surface which contacts with the standing area of the sole of the boot fastened in the binding, a tensile spring forming in said heel pull member the heel applied portion behind said yoke, a pair of compression springs accommodated in said heel spring at either end thereof and each connecting the rear end of one of said side parts with the adjacent end of said heel spring, said compression springs being substantially weaker than said heel spring, means affixed to the ski for engaging said yoke at places behind said places of permanent connection of said heel pull member with the ski to prevent deflection of said member between said permanent connections and said yoke inclusive, and a single manipulating lever which is turnably mounted on an axle in a support located outside the area of the boot and which is connected with said heel pull member, said support providing two spaced bearings for said lever axle, said lever being adapted in the one of said bearings to close and open the binding and in the other bearing to effect and release the engagement between said engaging means and said yoke, when the latter is being depressed by said boot on the ski, without the necessity of opening the binding.

6. A ski binding as claimed in claim 5, wherein an auxiliary lever is provided to co-operate with the manipulating lever, when the latter is positioned in the bearing to effect the engagement between said yoke and said engaging means, for lifting said manipulating lever off said bearing, said support having formed thereon guide ways

connecting said bearing with the other bearing to guide the lifted lever under the action of the heel spring automatically into the other bearing without opening the binding.

7. A ski binding secured to a ski and adapted to hold the boot worn by a skier to said ski, which comprises: a heel pull member secured at a plurality of points of attachment along its front portion to said ski, said heel pull member including side portions which extend along said ski; a 10 yoke member connecting said side portions of said heel pull member across the top face of said ski; means cooperating with said heel pull member behind said points of attachment of said heel pull member to said ski for preventing deflection of said heel pull member in advance of said points of attachment, said cooperating

means also acting to cause diagonal tension on the heel of a boot which is secured in said ski binding; and operating means for rendering said cooperating means operable, said operating means being positioned outside of the area on said ski occupied by the boot of the wearer.
